COMBINATION SNOWPLOW

William Frank Remus, Pembroke, Ontario,
Canada

Application April 18, 1933, Serial No. 666,741

8 Claims. (Cl. 37—44)

This present invention relates to certain new and useful improvements in a combination snow plow.

The primary object of the invention resides in the provision of a combination snow plow which is of simple and efficient structure and may be readily adjusted and regulated according to the conditions under which the snow plow is employed.

10 The invention has for another object the provision of a combination snow plow of the character stated including a special shoe at the forward end of the structure and carried by the front V-shaped scraper with which the forward or front plow may be readily raised or tilted, as desired.

15 The invention has for another object the provision of a combination snow plow of the character stated including special rear angularly adjustable scraper blades which may also be raised as well as adjusted angularly and brought closer together when required to assure the most efficient and satisfactory results according to the depth of the snow or ice on the surface and the hardness of the surface covering.

20 The invention has for a further object the provision of a combination snow plow of the character stated in which special shoes and front and rear scrapers or blades with the supporting and controlling members therefor may be readily mounted on a motor truck or the like of conventional design without requiring extensive alterations in the construction thereof.

25 The invention has for a still further object the provision of a combination snow plow of the character stated including readily operable controlling means for the front and rear scrapers and the front shoes with the actuating levers for the front shoe and front scrapers within ready reach of the operator so that these parts may be controlled by the operator without leaving his position in the cab or body of the motor truck.

30 The invention has for a still further object the provision of a combination snow plow of the character stated including special adjusting and control means for the rear scrapers whereby they may be readily adjusted and maintained in adjusted position from the rear of the motor truck or other body of the combination snow plow.

35 The invention has for a still further object the provision of a combination snow plow of the character stated in which all of the new and improved parts may be readily manufactured at small cost and mounted on the body and frame of a motor truck or the like with the minimum expenditure of time and labor to convert the motor truck or the

like into a motor snow plow which will be highly efficient for the purpose of thoroughly scraping and clearing the sides of a road bed and destroying ridges and other projections in the road bed.

40 The invention has for a still further object the provision of a combination snow plow of the character stated in which the specially manufactured scrapers and front shoe together with the other parts provided especially for mounting and controlling the same may be readily arranged on or removed from the body and frame or chassis of a motor truck or the like, as desired.

45 The invention has for a still further object the provision of a snow plow of the character stated which includes special cutter blades adjustable through the side longitudinal runners of the sleigh to destroy ridges and other projections in the road bed.

50 The invention has for a still further object the provision of a snow plow of the character stated which is constructed in such a manner that all of the adjustable parts are firmly mounted in the body of the plow structure and may be readily controlled by the operator, at all times.

55 To the accomplishment of these and related objects as shall become apparent as the description proceeds, my invention resides in the construction, combination and arrangement of parts as shall be hereinafter more fully described, illustrated in the accompanying drawings and pointed out in the claims hereunto appended.

The invention will be best understood and can be more clearly described when reference is had to the drawings forming a part of this disclosure wherein like characters indicate like parts throughout the several views.

In the drawings:—

Figure 1 is a side elevation of the improved combination snow plow, showing the special parts thereof mounted on the body and frame or chassis of a motor truck;

Figure 2 is a top plan with the body, engine, mud guards and running boards removed for the sake of clearness;

Figure 3 is a vertical longitudinal section, taken substantially on the plane of line 3—3 of Figure 2, looking in the direction indicated by the arrows;

Figure 4 is a detail fragmentary elevation, showing the locking means for locking the rear scrapers in their angularly adjusted positions;

Figure 5 is an enlarged fragmentary detail section, taken substantially on the plane of line 5—5 of Figure 1, looking in the direction indicated by the arrows;

- Figure 6 is a side elevation of a modified form of the invention;
- Figure 7 is a rear view of the modified form shown in Figure 6;
- 5 Figure 8 is a top plan view of the modified form of the invention;
- 10 Figure 9 is an enlarged fragmentary longitudinal vertical section, taken substantially on the plane of line 9—9 of Figure 8, looking in the direction indicated by the arrows; and
- 15 Figure 10 is a fragmentary detail view of the special slidable hinge connection employed between each of the transversely slidable bars and the rear side scraper blades.
- 15 Referring more in detail to the drawings, it will be noted that a substantially U-shape supporting bracket 11 is secured in the forward end of the frame or chassis 12 of a motor truck or the like by bolts 13 or other appropriate means. The main 20 portion of the bracket 11 is offset downwardly and converges toward its forward end or bight portion 14 which extends at a sharp angle to the angle to the legs or sides of the bracket 11. The bracket 11 extends for some distance past the forward end of the truck frame or chassis 12 and has a transverse bar 15 mounted on its forward portion and provided centrally with a pair of up-standing lugs 16 supporting therein the fulcrum bolt 17 for a pair of bell crank levers 18 and 19.
- 25 These bell crank levers 18 and 19 are employed for raising and lowering or tilting the substantially V-shape front shoe 20 having the special forward scraper blades 21 secured on its lower edge by bolts 22 or the like, recesses 23 being provided in the forward face of the front shoe 20 at its lower edge to receive the upper edges of said front scrapers 21 so that the outer faces of the front scrapers 21 are flush with outer face of the front shoe 20. These front scrapers 21 naturally 30 converge and meet at their forward ends. Both of the front scrapers 21 are curved from their upper edges to their lower edges to present concave outer faces and convex inner or rear faces. A scraper blade 24 is removably mounted on the forward face of each front scraper 21 at the lower edge thereof by bolts 25 or other appropriate means, the scraper blades 24 being curved slightly from their upper edges to their lower edges corresponding to the curve of the front scrapers 21.
- 35 The scraper blades 24 furthermore, have their lower cutting edges 26 bevelled or inclined rearwardly so that the scraper blades 24 may have sharp lower edges to effectively cut away ridges and the like on the road bed. The curved or 40 arcuate lower arm 27 of the bell crank lever 18 is bifurcated and has its branches loosely connected as by means of link connections 28 with the rear transverse bar 29 connecting the diverging branches of the front shoe 20, beneath the bracket 45 11. The long upstanding arm 30 of the bell crank lever 18 is pivotally connected with an actuating bar lever 31 which extends rearwardly over the engine casing 32 of the motor truck and into the body or cab 33 thereof, a hand grip 34 being 50 provided on the free rear extremity of the bar lever 31 by means of which the operator may readily actuate the bar lever 31 and set the same in adjusted position by catching the proper rack teeth 35 on the underface of the bar lever 31 in the plate 36 through which the bar 31 operates, within the motor truck body or cab 33. The lower arcuate arm 37 of the bell crank lever 19 is likewise loosely connected by a link connection 38 or the like with the forward transverse bar 39 connecting the branches of the front shoe 20 be-
- 5 low and forwardly of the bracket 11. The long upstanding arm 40 of the bell crank lever 19 is pivotally connected to the forward lower end of the bar lever 41 for controlling the same and which projects into the body or cab 33 of the motor truck with an appropriate hand grip 42 on its rear end by means of which the operator may readily actuate the bar lever 41. This bar lever 41 also has rack teeth 43 on its lower face adjacent its rear end for locking engagement with the plate 44 in the motor truck body or cab 33 and through which the bar lever 41 extends. It is apparent that by actuation of the bar levers 31 and 41, the forward end or the rear end of the front shoe 20 and parts carried thereby may be tilted as desired or by actuation of the bar levers 31 and 41 together, the front shoe 20 and parts carried thereby may be raised or lowered vertically. During raising and lowering of the front shoe 20 and parts carried thereby, the angular guides 45 carried on the inner face of the shoe 20 at opposite sides thereof serve to guide the shoe 20 with friction reduced to the minimum, as the angular guide bars 45 are located opposite the forward corners of the bracket 11.
- 25 Mounted transversely beneath the frame or chassis 12 at the centre thereof or just rearwardly of the centre, is a rear scraper supporting bar 46 having a pair of straps 47 mounted on its opposite ends and projecting slightly from the sides of the motor truck chassis 12 and supporting up-standing hinge pins 48 on which are mounted the hinge plates 49 of the pair of diverging rear scrapers 50, the hinge plates 49 being secured on the rear or inner faces of the rear side scrapers 50 and projecting from the forward ends thereof. The hinge plates 49 are of arcuate form with collars 51 on their projecting upper and lower ends and which collars 51 are loosely mounted on the upper and lower portions of the respective up-standing hinge pins 48. It will thus be seen that the rear side scrapers 50 may be adjusted vertically on the hinge pins 48 and retained in their vertically adjusted position by small collars 52 positioned on the hinge pins 48 below the lower collars 51 and secured in their adjusted positions vertically of the hinge pins 48 by securing pins 53 or the like passed through the collars 52 and through the selected openings of a series of spaced openings 54 extended transversely through the lower portions of the upstanding hinge pins 48. The rear side scrapers 50 are straight from their upper edges to their lower edges with scraper blades 55 secured on their lower edges and curved outwardly therefrom with the bottom edges of said scraper blades 55 bevelled on their under faces so as to present sharp lower edges which will effectively cut away ridges or the like on the sides of the road bed. Upstanding vertical hinge bars 56 are provided on the inner faces or rear faces of the rear side scrapers 50 just forwardly of the centre thereof. These hinge bars 56 have slidably thereon the collars 57 provided at the outer ends of hinge plates 58 which are hingedly mounted on the rear faces of a pair of transversely movable rack bars 59 sliding through guide loops 60 on a supporting plate 61 mounted transversely on the rear portion of the motor truck chassis 12, rack teeth 62 being provided on the forward faces of the rack bars 59 from their overlapping inner ends for the greater portion of the length of said rack bars 59. The rack bars 59 are operated together to force the rear side scrapers 50 outwardly from one another or draw them inwardly toward one another on the up-
- 75

standing hinge pins 48, by means of a pinion 63 positioned between said rack teeth 62 thereof, said pinion 63 being carried on the upper end of a stub shaft 64 rotatable through the plate 61 and through a bearing 65 positioned beneath said plate 61. A bevelled gear 66 is carried on the lower end of the stub shaft 64 and operated by a bevel gear 67 meshing therewith and carried on one end of an operating shaft 68 which in turn 10 is carried in appropriate bearings 69 swung beneath the motor truck chassis 12, the shaft 68 extending rearwardly and projecting from the rear end of the chassis 12 with an actuating crank 70 on its rear extremity. To lock the shaft 15 68 against unauthorized rotation and thus maintain the rear side scrapers 50 in set adjustment, a ratchet wheel 71 is rigidly mounted on the shaft 68 and normally engaged by a double reversible pawl 72 having its arms or branches directed 20 at right angles and the free ends 73 thereof slightly turned or bent in opposite directions for positive locking with the teeth or the ratchet wheel 71, said double reversible pawl 72 being mounted at its centre on a fulcrum member 74 carried 25 on the rear of the chassis 12. To reduce friction to the minimum during adjustment of the rear side scrapers 50, a pair of grooved anti-friction rollers or idlers 75 are mounted on the plate 61 with their peripheries engaged against 30 the outer faces of the respective rack bars 59. The rear side scrapers 50 are brought in close to the sides of the motor truck chassis 12, inwardly of the free rear ends of the diverging branches of the front shoe 20 and the front 35 scraper blades 24 carried thereby so as to catch all snow and ice and the like cut from the surface and thrown out by the front scraper blades 24. Furthermore, the rear side scrapers 20 are of considerable length, thus permitting proper adjustment 40 of the same to assure cutting away of ridges and the like from the centre of the road bed to the outer side edges of the road or as near to the same as desired.

As the construction of the device has thus 45 been described in detail, brief reference is now had to its use and modus operandi: The front shoe 20 and parts carried thereby are raised and lowered or tilted either forwardly or rearwardly as desired, by proper manipulation of the 50 bar levers 31 and 41 by the operator while still in his position within the body or cab 33 of the motor truck. Adjustment of the rear side scrapers 50 and the scraper blades 55 carried thereby is accomplished, however, when the snow plow is 55 stationary. The rear side scrapers 50 may be readily raised or lowered on the hinge pins 48 and the collars 52 secured in adjusted position below the lowermost collars 51 thus assuring retention of the rear side scrapers 50 and blades 55 in vertically adjusted position. The shaft 68 60 may be readily manipulated by the crank 70 for swinging the rear side scrapers 50 outwardly and inwardly on the hinge pins 48 when the pawl 72 is thrown on its fulcrum member 74 to inoperative or non-functioning position.

In the modified form shown in Figures 6 to 10 inclusive, the machine includes a body 76 having side runners 77 supported along the sides thereof by transverse beams 78 extended beneath the body 76 and connected at their opposite ends with the inner sides of the runners 77. An additional brace bar 79 is extended across the forward portions of the side runners 77 outwardly of the forward end of the body 76 to further brace and 75 strengthen the side runners 77. A tongue carry-

ing bar 80 is extended across the front of the side runners 77 and rotatable in bearings 81 carried on said runners 77. A draft tongue 82 has its rear end secured to the centre of the bar 80 and the draft tongue 82 is braced by angularly extended brace bars 83 which have their rear ends turned and secured to the bar 80 by appropriate fastening means 84, while the forward ends of the brace bars 83 are also turned and secured on opposite sides of the draft tongue 82 by appropriate fastening means 85.

The forwardly converging front scraper blades 86 have their forward ends meeting and firmly fastened together and the upwardly curved front shoe 87 is secured to the connected forward ends 15 of the front scraper blades 86. The shoe 87 is preferably formed of a metal bent upon itself with the lower end 88 of the material secured beneath the connected ends of the front scraper blades 86, while the other end 89 of the front 20 shoe material is extended upwardly and then bent down over the scraper blade supporting plates 90 on which the blades 86 are carried, said end 89 being bent around and secured on a transverse pin 89a extending through the plates 90. In 25 order that the front scraper blades 86 may be readily raised and lowered or tilted to the desired incline, the plates 90 are loosely connected to the forward ends of the side runners 77 by 30 slide hinges 91. These plates 90 are connected by 35 a transverse connecting bar 92, forwardly of the body 76 and the side runners 77 and a pair of rearwardly converging bar levers 93 have their forward ends hinged to the bar 92, near the ends 40 of the latter. These bar levers 93 extend over and rock on the transverse bar 79, beneath the bar 80. Owing to the main portion of the bar 80 being raised or offset upwardly, the bar levers 93 may be operated without interference by the bar 80.

Each side runner 77 has at its centre a longitudinally elongated vertical slot 94 which has its forward and rear walls inclined so that the top of the slots 94 are longer than the bottom thereof. Working in each slot 94 is a wide knife 95 45 having its lower end 96 bevelled and slightly turned forward. Each knife 95 is adjustable vertically within its respective slot 94 and is slidable through a loop guide 97 carried on the inwardly offset end 99 of a U-plate 98 supported 50 in the slot 94 by means of a bolt 100 extended transversely through the centre of the slotted portion of the side runner 77, near the upper edge thereof. The knives 95 are each raised and lowered in their respective slots 94 and thus adjusted to the proper height within the side runners 77, by means of a slightly curved finger 101 55 provided on the bevelled forward end 102 of a lever 103, by bifurcating the same. Each lever 103 is carried on a fulcrumed member 104 extended 60 transversely through an upstanding bracket 105 on the side runner 77 for which the knife 95 is provided. Each lever 103 is then extended upwardly and carries a conventional spring latch 106 for automatic locking engagement with the segmental rack 107 positioned adjacent the lever 103, so that the latter may be readily locked in adjusted position. When either lever 103 is to be re-adjusted for raising or lowering the knife 95 controlled thereby, the lever 70 103 may be readily released from the segmental rack 107 by the conventional releasing finger 108 provided for this purpose on the lever 103. It will, therefore, be apparent that the knives 95 75 may be independently adjusted and as the levers 75

103 converge toward one another, as they are extended upwardly and rearwardly, they may be readily operated by the attendant on the body 76, the same as the levers 93 which are forwardly 5 of the levers 103. Hoods 109 are positioned over the slots 94 and extended outwardly over the sides of the body 76, to discharge to the sides of the machine, the material cut by the blades 95 and rising in the slots 94.

10 The pair of rear side scraper blades 110 are carried on the guide wings 111 which are hinged at their forward ends to the outer faces of the side runners 77, rearwardly of the centres of the latter, by appropriate hinges 112. The wings 15 111 diverge rearwardly and the transversely sliding supporting bars 113 for the wings 111 have their outer ends connected to the inner faces of the wings 111 at about the centre thereof, by the loose hinges 114, straps 114a of which are hinged 20 on the respective bars 113. Supporting bars 113 slide transversely across the rear portion of the sleigh body 76 with their inner ends overlapping, owing to positioning of one of the bars 113 in a plane slightly forwardly of the other 25 with the planes parallel to one another. Each of the bars 113 carries a loop guide 115 projecting laterally therefrom and through which the other bar 113 slides. Both of the bars 113, at their overlapped portions are adjustable through 30 a larger loop guide 116 formed by offsetting upwardly a portion of the strap 117 secured longitudinally on the body 76, so that the bars 113 may be readily adjusted transversely of the body 76 to regulate independently the angle of each 35 of these wings 111 and the rear scraper blade 110 carried thereby. A set screw 118 or other means is employed for securing the bars 113 in adjusted position in the loop 116.

As the construction of this modified form has now been fully described, brief reference is now had to the use and modus operandi thereof: It is to be noted that the snow plow could be drawn by any appropriate power connected with the tongue 82. The body 76 of the machine is firmly supported on the side runners 77 which ride on the road bed and permit adjustment of the front scraper blades 86; the knives 95 and the rear scraper blades 110, independently, by the attendant on the body 76. The rear scraper blades 110 continue the scraping work of the forward front scraper blades 86 and serve to throw the loosened material to either side of the road bed. At the same time, the knives 95 may be employed for cutting away ridges or projections on the road surface such as the side walls of ruts, formed by the wheels of motor vehicles, wagons or the like, so as to present a smooth surface the entire width of the road bed. These knives 95 may be readily adjusted to correspond or independently of one another, by separate adjustments of the levers 103 for the respective knives 95. All of the adjustments may be readily effected by the attendant while positioned on the body 76 of the snow plow and the adjustment may be made without interfering with proper functioning of the side runners 77 or the connection of the snow plow with its draft means.

70 From the foregoing description taken in connection with the accompanying drawings, it will be manifest that a combination snow plow is provided that will fulfill all the necessary requirements of such a device, but as many changes could be made in the above description, and many apparently widely different embodiments of my invention may be constructed within the scope

of the appended claims without departing from the spirit or scope thereof, it is intended that all matters contained in the said accompanying specification and drawings, shall be interpreted as illustrative and not in a limitative or restrictive sense.

Having thus described my invention, what I claim as new and desire to secure by Letters Patent is:—

1. A combination snow plow including a frame 10
or chassis; a front shoe supported on said frame
or chassis; means for tilting either the forward
or rear portion of said shoe separately or raising
and lowering said forward and rear portions of
the shoe together; angles on opposite faces on 15
the inside of said shoe adapted to bear against
said frame or chassis for guiding said shoe when
raising and lowering the same; front scraper
blades carried by said shoe; a pair of rear side
scrapers; blades for said scrapers; means for 20
hingedly mounting said rear side scrapers and
blades at the sides of said chassis and adjusting
said rear side scrapers and blades vertically; and
means controlled from the rear of said chassis
for adjusting said rear side scrapers and blades 25
toward and away from one another.

2. A combination snow plow including a supporting frame or chassis; a front shoe adjustable vertically on the forward end of said frame; front scraper blades carried by said front shoe; a pair of reciprocating control rods and bell cranks for adjusting said front shoe vertically and tilting the forward and rear portions thereof; a pair of rear side scrapers hinged to said frame or chassis and adjustable vertically thereon and means for swinging said rear side scrapers on their hinges and adjusting the distance between the rear portions of said rear side scrapers; and rear side scraper blades carried by said rear side scrapers.

3. A combination snow plow including a frame 40 or chassis; a bracket extended forwardly from said frame or chassis; a front shoe adjustable vertically on said bracket; front scraper blades carried by said front shoe; means operating on said bracket and connected with said front shoe 45 to raise and lower the same on said bracket and to tilt the forward and rear portions of said shoe selectively; guide means for said front shoe bearing against the front and sides of said bracket; rear side scraper blades adjustably hinged 50 to said chassis; and means for controlling spreading of the said rear scrapers on said chassis.

4. A combination snow plow including a frame or chassis; a pair of rear scrapers hinged at their forward ends on the sides of said frame or chassis and adjustable vertically thereon; a pair of transverse rack bars slidable over said frame or chassis, limited to horizontal movement, and having their outer ends connected with the rear portions of said rear side scrapers by an adjustable hinge connection allowing of relative vertical movement; scraper blades carried by said rear side scrapers; means to control operation of said rack bars for spreading said rear side scrapers and drawing the latter toward one another; a front shoe adjustably mounted on said frame or chassis; and controlling and adjusting means for said front shoe; said front shoe having front scraper blades on its lower edge.

5. A combination snow plow including in combination with a frame or chassis; a forwardly converging downwardly offset bracket secured thereon; a transverse bar mounted thereon; a pair of oppositely directed bell cranks fulcruming on said bar; a vertically adjustable front shoe 75

engaging the forward end of said bracket and connecting to said bell cranks so that it can be raised or lowered at the front or rear, separately or simultaneously; front scraper blades carried by 5 said shoe; and rear side scrapers and scraper blades for adjustable hinging and mounting on the sides of the said frame or chassis.

6. A combination snow plow including in combination with an automobile frame or chassis; a 10 forwardly converging downwardly offset bracket secured thereon; a transverse bar mounted thereon; a pair of bell cranks fulcruming on said bar; the lower arms of said bell crank being oppositely directed and bifurcated laterally; a V-shaped front shoe; angular guides on the inner 15 faces of the converging bracket of said shoe extending vertically for the height thereof to engage opposite sides of the forward end of said bracket; forward and rear transverse bars across said 20 front shoe to which the bifurcated lower arms of said bell crank respectively connect; means for manipulating said bell crank; and rear side scrapers and scraper blades for adjustable hinging and mounting on the sides of said frame or 25 chassis.

7. A combination snow plow including in combination with an automobile frame or chassis; a forwardly converging downwardly offset bracket secured thereon; a transverse bar mounted thereon; a pair of bell cranks fulcruming on said bar; the lower arms of said bell cranks being oppositely directed and bifurcated laterally; a V-shaped front shoe; angular guides on the inner 30 faces of the converging bracket of said shoe extending vertically for the height thereof to engage opposite sides of the forward end of said bracket; forward and rear transverse bars across 35

said front shoe to which the bifurcated lower arms of said bell crank respectively connect; an actuating bar lever pivotally connected to the upper arm of each of said bell cranks, extending rearwardly over the hood of the automobile and into the body or cab thereof; a hand grip on the free rear end of each of said bar levers; rack teeth on the underface of each of said bar levers near said free rear end; a fixed plate through which said bar levers project and on which said 10 rack teeth are adapted to selectively catch; and rear side scrapers and scraper blades for adjustable hinging and mounting on the sides of the said frame or chassis.

8. A combination snow plow including in combination with a frame or chassis, a front shoe, transversely perforated hinge pins one on each side of said chassis near the rear thereof, rear scraper blades each having a hinge plate on its forward inner end, said hinge plates being of 20 arcuate form with a collar formed on both upper and lower ends and aligned to receive said hinge pins, supporting collars secured in desired positions on said hinge pins by removable securing pins for supporting said scraper blades, elongated vertical hinge bars on the inner sides of 25 said scraper blades intermediate their ends, sliding hinge plates free to move vertically on said hinge bars, horizontally sliding rack bars carrying said sliding hinge plates on their outer ends, a supporting plate on said chassis, spaced guide 30 loops thereon for said rack bars, a crank actuated pinion on said supporting plate engaging confronting faces of said rack bars between said guide loops, and backing idlers for said rack bars 35 opposite said pinion.

WILLIAM FRANK REMUS. [L. S.]
